ABSTRACT

A sheet conveyor device for automatic copying machine where a suction tank has rollers positioned therearound for endless belts to be driven thereon, and suction holes are located in said tank between the belts. A guide sheet extends around most of the suction tank and is closely spaced thereto so that a sheet of paper can be passed between said guide sheet and the belts and held against the belts by the suction.

FIG. 1

FIG. 2

FIG. 3

SHEET CONVEYOR FOR AUTOMATIC COPYING MACHINES

BACKGROUND OF THE INVENTION

The present invention relates to an automatic copying machine and more particularly a sheet conveyor for automatic copying machines.

It is very difficult in automatic copying machines to transport securely and uniformly sheets such as tracing paper which have a very small thickness, a poor strength and a tendency of being easily curled, without causing any damage to them. This difficulty is met not only in the case of transporting along a planar surface but also in the case of conveying a curved surface having a small radius of curvature. The difficulty is increased especially in the latter case.

As a device for conveying such sheets or the like of the character described above, there has been used a device wherein a plurality of conveyor belts are spaced apart from each other upon a suction tank having suction holes so that the sheets or the like may be firmly pressed against the conveyor belts by the suction of the air into the sheet or the like does not seal the suction holes, the surrounding air is unnecessarily sucked through these holes, so that the suction of the tank is reduced and the sheet or the like cannot be firmly pressed against the conveyor belts as desired.

One of the objects of the present invention is therefore to provide a device which can ensure the positive, secure and uniform transportation of the sheets or the like in the conveyor system of the type described above.

Another object of the present invention is to provide a sheet conveyor device of the type described above which enables the sheets or the like to be transported along a vertical surface and a ceiling.

SUMMARY OF THE INVENTION

According to the present invention, the conveyor belts are closely covered with a guide sheet having a width equal to or slightly larger than the over-all width of the conveyor belts. The sheet or the like is transported by the conveyor belts under the guide sheet while the sheet or the like is firmly pressed against the belts by the above described suction. Since the guide sheet is closely pressed against the conveyor belts at the portion where no sheet or the like is interposed therebetween, the air to be sucked into the tank through the suction holes upon which is not passing the sheet or the like is remarkably reduced in quantity. This means that the sheet or the like is sucked and pressed against the conveyor belts with an increased force. Thus, the sheet or the like may be positively, securely and uniformly transported without causing any damage in a well safe-guarded manner.

The above and other objects, features and advantages of the present invention will become more apparent from the description of one illustrative embodiment thereof with reference to the accompanying drawing.

BRIEF DESCRIPTION OF THE DRAWING

FIG. 1 is a diagrammatic view for explanation of a sheet conveyor device in accordance with the present invention;

FIG. 2 is a fragmentary side view thereof with parts broken away; and

FIG. 3 is a cross sectional view thereof illustrating the sheet or the like being transported.

DESCRIPTION OF THE PREFERRED EMBODIMENT

Referring to FIGS. 1 and 2, an opening 2 is formed at a suitable portion of one side of a suction tank 1 and is connected to one end of a conduit pipe 3 leading to a suction pump (not shown) so that the air within the tank is always discharged therefrom, thereby maintaining the pressure negative relative to the atmospheric pressure. An endless belt 4 is wrapped over rollers 5, 6, 7 and 8 so as to be advanced in the direction indicated by the arrow around the tank 1.

The endless conveyor belt 4 is comprised of a plurality of equidistantly spaced apart belts and suction holes 9 are formed in the side wall of the tank 1 in opposed relation with the spaces between the belts or strips. The suction holes 9 may be of slit shape.

A guide sheet 10 is made of a material such as plastics or sheet metals having a high-grade surface smoothness and a better air-tightness and incapable of generating electrostatic charge (electrification). The guide sheet 10 is disposed outwardly of the belt 4.

When a sheet of paper 11 is inserted between the conveyor belt 4 and the guide sheet 10 through an inlet in the direction indicated by the arrow in FIG. 1, the sheet 11 is transported by the conveyor belt 4. In this case, sheet 11 is sucked and pressed against the conveyor belt 4 by the air sucked into the suction tank 1 through the suction holes 9 formed in the side wall thereof. This is illustrated in FIG. 3. That is, the sheet 11 being conveyed by the conveyor belt 4 is subjected to the suction at the spaces between the belts by the air sucked into the tank through the suction holes 9. Therefore, the sheet 11 may be securely held upon the conveyor belt while it is advanced. There is no suction in the space between the conveyor belt 4 and the guide sheet 10, so that the transportation of the sheet 11 will not be adversely affected even when the surface of the guide sheet 10 is rather rough.

Only the upper end portion 12 of the guide sheet 10 may be held in position whereas the lower end may be free upon a support 13 when the copying machine is in anoperative position because when the machine is once operated, the guide sheet 10 may be tightened upon the conveyor belt 4 due to the tension applied to the guide sheet 10 from the conveyor belt 4 and the suction described hereinabove.

There has been used an arrangement and construction in which a guide plate is spaced apart from the conveyor belt 4 by a small distance without employing the guide sheet 10 of the character described above. However, in this case, it is not ensured that the sheet 11 is securely pressed against the conveyor belt 4 so that the sheet is for example curled, thus resulting in the difficulty in transporting the sheet or the like 11 smoothly without causing any deformation thereof. There has been also proposed a method in which another conveyor belt is extended over the conveyor belt 4 so as to be driven together. However, the tension present in the exterior conveyor belt will act upon the sheet or the like to be transported. This is not preferable and the construction is complicated.

However, according to the present invention, the sheet or the like is pressed securely against the conveyor belt by the suction due to the negative pressure in the suction tank so that the sheet may be smoothly transported not only along the planar surface but also the curved surface having a small radius of curvature. Furthermore, sheets which easily tend to curl may be transported in a well safe-guarded manner and may be transported even along the ceiling. Since the guide sheet of the present invention is attracted toward and seals the suction ports other than those acting upon the sheet being conveyed, it is positively prevented that the air is unnecessarily sucked through these idle suction holes into the suction tank, thereby decreasing the negative pressure within the tank.

The suction only acts upon the sheet 11, not upon the guide sheet 10, so that there is no special acting therebetween so as to adhere them. Thus, the guide sheet 10 will not adversely affect the transportation of the sheet 11.

Preferably, the guide sheet is made of a transparent material so that the transportation of the sheet can be checked from the outside.

It will be, of course, understood that the device in accordance with the present invention is not only applied to an automatic copying machine but also to any other conveyor system or the like.

I claim:

1. A sheet conveyor device for passing a sheet of paper through an automatic copying machine comprising

a suction tank mounted within the machine and having an end area including a feed portion and an exit portion for said paper;

a plurality of rollers spaced around the periphery of said suction tank and extending outside of the periphery of said suction tank;

a plurality of endless belts having a predetermined total transverse dimension and mounted to be

driven on said rollers, said belts located on said rollers to provide a predetermined spacing area between adjacent belts;

individual groups of suction holes formed in said suction tank, each individual group located solely in one of said predetermined spacing areas respectively;

a guide sheet of a flexible nature located in the machine, said guide sheet having vertically spaced and aligned inlet and outlet end portions adjacent said end area of said suction tank, said guide sheet having a configuration to be disposed outwardly of an adjacent to said endless belts;

said guide sheet projecting inwardly into the machine from said end area and extending around said plurality of endless belts from said feed portion to said exit portion; and

said guide sheet having a transverse dimension greater than said predetermined total transverse dimension of said plurality of endless belts whereby the paper passing through the machine between said guide sheet and said belts is held against said belts by suction acting through said holes.

2. A sheet conveyor device according to claim 1 in which said inlet end portion of said guide sheet is secured in the machine and located vertically above said outlet end portion, and said outlet end portion is positioned to move freely with respect to said machine.

3. A sheet conveyor according to claim 2 in which an element is located within the machine to provide a support for said freely movable outlet end portion of said guide sheet.

4. A sheet conveyor according to claim 1 in which said transverse dimension of said guide sheet is such that its outer transverse edge extends further outwardly than an outermost located belt in said plurality of endless belts.
